DISPENSING FAUCET OR SIMILAR ARTICLE

Ronald J. Mrugala, Brooklyn Park, Minn., assignor to
The Cornelius Company, Anoka, Minn.

Filed June 28, 1971, Ser. No. 157,791

Term of patent 14 years

Int. Cl. D23—01

U.S. Cl. D23—23

FIG. 1 is a front elevational view of a dispensing faucet or similar article, showing my new design;

FIG. 2 is an elevational view of the right side thereof;

FIG. 3 is an elevational view of the left side thereof; and

FIG. 4 is a top plan view thereof.

The rear is plain and unornamented.

I claim:

The ornamental design for a dispensing faucet or similar article, substantially as shown and described.
